(57) **CLAIM**

The ornamental design for a stroller part, substantially as shown and described.

DESCRIPTION

FIG. 1 is a top, front, left side isometric view of a stroller with the stroller part of the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The portions of the stroller depicted in broken lines are provided to show the environment in which the stroller part is used and do not form a part of the claimed design.
